Attorneys.

UNITED STATES PATENT OFFICE.

BENJAMIN L. BLAIR, OF INDIANAPOLIS, INDIANA.

AIR-GUN DISCHARGE MEANS.

1,314,850.

Specification of Letters Patent.

Patented Sept. 2, 1919.

Application filed April 13, 1917, Serial No. 161,791. Renewed January 10, 1918. Serial No. 211,312.

To all whom it may concern:

Be it known that I, BENJAMIN L. BLAIR, a citizen of the United States, residing at Indianapolis, in the county of Marion and 5 State of Indiana, have invented certain new and useful Improvements in Air-Gun Discharge Means, of which the following is a specification.

The object of this invention is to provide 10 manually operated means for actuating the discharge mechanism of air-guns, which will be durable, reliable, and inexpensive to manufacture and maintain.

The further object is to provide a device 15 for the purpose intended which will be set by the same mechanism which inserts a projectile in the barrel to be discharged.

I accomplish the above and other objects 20 which will hereinafter appear, by the mechanism illustrated in the accompanying drawing, in which—

Figure 1 is a longitudinal vertical section through the gun-casing, showing my invention in side elevation, with the parts set 25 ready to shoot. Fig. 2 is a horizontal section of the gun-casing showing my invention in plan view as the parts are after a discharge, in full lines, and set for shooting, in dotted lines. Fig. 3 is a section on the 30 line 3—3 of Fig. 2, enlarged, and Fig. 4 is a section on the line 4—4 of Fig. 1, enlarged.

Like characters of reference indicate like parts in the several views.

The base 5 supports the operative parts 35 of my device, and is itself supported by a yoke 6, to which it is pivoted, which yoke is supported from a sub-base, not shown. Compressed air, from a suitable source (not shown) is supplied through a pipe 7, to the 40 interior of a cylinder 8, which discharges through a nozzle 10, into a projectile barrel 11. Projectiles 12 are supplied by gravity from a chute 13. The barrel is moved from the position shown in Fig. 1 to that 45 shown in Fig. 2, to load, by means comprising lateral arms 14, which are connected with a pair of rods 15, which extend toward the breech of the gun and pass through a guide bar 16, supported in a fixed position from the base 5. Near the bar 16 is a cross bar 17, having its ends fixed to the two rods whereby the rods will be moved longitudinally by moving the bar, thereby moving the barrel into contact with the cylinder 8, or 55 away therefrom, as desired. A fixed arm

18 is fastened to the bar 17, and extends rearwardly, and to its end a rod 18' is hingedly jointed. The other end of the rod is pivotally connected with the end of a crank on a vertical rock-shaft 19, supported 60 by base 5, and on the end of the rock-shaft below the base is a lever 20, by which the shaft 19, is manually rocked.

The mechanism for admitting the compressed air to the projectile barrel 11, is 65 controlled by the movement longitudinally and inwardly of a rearwardly projecting rod 21, which is made normally and initially to project by a spring 22'. The inward movement of the rod 21 is effected by the 70 contact of a rotating cam 22, with the end of the rod. The cam is loosely mounted on a shaft 23, journaled between the two parallel bars of a frame 24. The cam has a half clutch on one side which is forced by a 75 spring 26, into engagement with a half clutch on a sheave 25, mounted in a fixed manner on the shaft. On the other side of the cam from the sheave 25 outside of the frame 24, is a second sheave 27, also mounted 80 in a fixed manner on the shaft, and integral with sheave 27 is a ratchet wheel 28, having a notch which is engaged by a pawl-lever 29, pivoted to the frame 24, and normally pressed by a spring 30, against the wheel 28. 85 The free end of the pawl-lever is connected by a wire 31, with a trigger-lever 32, pivoted as shown, in the hollow of a handle 33, on a disk 34 at the end of the gun.

Attached at one end to the sheave 27, and 90 wrapped under it is a chain 35, which is fastened to a spring 36, in turn fastened to the disk 34.

Carried by the movable cross-bar 17, is a tube 48, which houses a spring 37. The inner end of the spring is fastened to a threaded eye-bolt 38, and on the latter, against the end of the tube, is a nut 39. The other end of the spring is fastened to a chain 40, which extends to and is fastened to the 95 sheave 25, passing over the top of the latter. The tension of the spring in the tube attached to the chain, is regulated by the adjustment of the nut on bolt 38. The pull of this spring is made enough greater than 100 that of spring 36, to rotate the shaft 25 against the resistance of the latter, when the pawl 29 is disengaged.

The operation of my device is as follows: Assuming that the gun has been discharged 110

and it is desired to reload and set it for another discharge; the hand lever 20, is moved in the direction of the arrow, Fig. 2, to the position shown by the dotted lines. 5 This moves the crank on rock-shaft 19 from the position shown in Fig. 1, to that shown in Fig. 2, and moves the cross-bar 17 from the position shown by dotted lines in Fig. 2, to the position shown by the full lines, which 10 carries with it the tube 48 and spring 37, and releasing the chain to which it is attached allows the chain pulled by the spring 36, to rotate the shaft through sheave 27, and through its clutch connection with the shaft, 15 to rotate the cam to the position shown in Fig. 3. At the same time the barrel 11 is moved away from the air cylinder to admit a projectile. Then, when the hand lever 20 is returned to its first position, the barrel 20 11 is closed and the cross-bar 17 is returned to the position shown in Fig. 1, which tightens the spring 37 and its chain, and would reverse the rotation of shaft 23, but for the pawl 29. The gun is then in position 25 to shoot, and will be discharged by the withdrawal of the pawl, by pulling manually on the trigger 32. Then the action of spring 37 rotates the shaft and cam, causing the cam to press the rod 21, inwardly. 30 Having thus fully described my invention and illustrated it by the most approved details now known to me, but to which details I do not desire to be unduly limited, nor indeed, more than is pointed out in the 35 claims, what I do claim as new and wish to secure by Letters Patent of the United States, is—

1. In an air gun, the combination of an air container having a push-rod actuated 40 discharger, of a rotatable cam adapted to contact with and push in said rod, spring means to operate the cam, means to set the spring, a pawl and ratchet means to hold the set spring, and a trigger means to release the 45 spring.

2. In an air gun, the combination of an air container having a push-rod actuated discharger, of a rotatable cam adapted by rotation to contact with and push in said 50 rod, spring means to rotate the cam, means to temporarily release the tension of said spring, means comprising a second spring to set the cam while the tension of the first spring is temporarily released, a pawl and ratchet means to hold the set cam against the restored action of the first spring, and a trigger means to disengage the pawl and release the first spring.

3. In an air gun, the combination of an air container having a push-rod actuated 60 discharger, a rotatable cam adapted by rotation to contact with and push in the rod, spring means to rotate the cam when set, means to load the gun and simultaneously set the spring, and trigger means to 65 liberate the set spring.

4. In an air gun, a compressed air container, a push-rod projecting therefrom, a shaft, a cam loosely mounted on the shaft, a sheave fixed on the shaft, said cam and sheave having interlocking clutch halves, a spring pressing the cam toward the sheave, a chain and spring means to rotate the shaft, means for releasing the tension of the 70 spring, means to wind up the chain on the sheave while the tension of the spring is released, pawl and ratchet means to hold the tension and a trigger means to disengage the 75 pawl.

5. In an air gun, a compressed air container, a push-rod projecting therefrom, a shaft, a cam loosely mounted on the shaft, a sheave fixed on the shaft, said cam and sheave having interlocking clutch halves, a spring pressing the cam toward the sheave, 80 a chain and spring means to rotate the shaft, means for moving the spring toward the sheave to release the tension, means to wind the chain on the sheave while the tension of the spring is released, pawl and ratchet 85 means to hold the shaft when the tension of the spring is restored by moving it away from the shaft, and a trigger means to disengage the 90 pawl.

6. In an air gun, a compressed air container, a push-rod projecting therefrom, a shaft, a cam loosely mounted on the shaft, a sheave fixed on the shaft, said cam and sheave having interlocking clutch halves, a spring pressing the cam toward the sheave, 95 a chain and spring means to rotate the shaft, means for moving the spring toward the sheave to release its tension, means to wind the chain on the sheave while the tension of the spring is released comprising a second 100 sheave fixed on the shaft, a chain and weaker spring than the first, attached to the second sheave, pawl and ratchet means to hold the shaft when the tension of the first spring is 105 restored by moving it away from the sheave, 110 and a trigger means to disengage the pawl.

In witness whereof, I have hereunto set my hand and seal at Indianapolis, Indiana, this 22nd day of March, A. D. one thousand nine hundred and seventeen.

BENJAMIN L. BLAIR. [L. S.]
